[57] CLAIM

The ornamental design for a immunoassay test slide, substantially as shown and described.

DESCRIPTION

FIG. 1 is a top plan view of an immunoassay test slide, showing our new design;

FIG. 2 is a left side elevational view thereof;

FIG. 3 is a right side elevational view thereof;

FIG. 4 is a bottom plan view thereof;

FIG. 5 is a sectional view taken along line 5—5 of FIG.

1;

FIG. 6 is a rear elevational view thereof;

FIG. 7 is a front elevational view thereof.

FIG. 2

FIG. 3

FIG. 6

FIG. 7

FIG. 5
